Patented Aug. 15, 1967

208,305

1/4 RACK METERED POWER SUPPLY MODULE

Lester Dubin, 514 Esplanade, Pelham Manor, N.Y.
10803; Maury Paulson, 2 Valley St., Huntington, N.Y.
11743; and Benjamin Shmurak, 15 Stuart St., Lynbrook,
N.Y. 11563

Filed Mar. 23, 1965, Ser. No. 84,413

Term of patent 14 years

(Cl. D26—1)

FIG.-1

FIG.-2

FIG.-3

FIG. 4

FIGURE 1 is a front elevational view of a 1/4 rack metered power supply module showing our new design; FIGURE 2 is a fragmentary top plan view thereof; FIGURE 3 is a rear elevational view thereof; and FIGURE 4 is an isometric view thereof.

The essential features of our design are shown in full lines.

We claim:

The ornamental design for a 1/4 rack metered power supply module, as shown and described.
